L. MACHADO

MOTOR VEHICLE HEATING ATTACHMENT

Filed Dec. 4, 1925

Inventor:
Louis Machado
by Right Brown Quincy May

Attys.

UNITED STATES PATENT OFFICE.

LOUIS MACHADO, OF HINGHAM, MASSACHUSETTS.

MOTOR-VEHICLE HEATING ATTACHMENT.

Application filed December 4, 1925. Serial No. 73,168.

This invention relates to means for utilizing the waste heat from the motor of an automobile, to warm the body of the vehicle by causing a current of air induced by the forward motion of the vehicle to flow through a drum surrounding a portion of the exhaust pipe of the engine, and enter the body of the vehicle in a heated condition.

The objects of the invention are to provide a drum of improved construction, composed of sections adapted to be quickly and conveniently assembled on the exhaust pipe, and form a drum subdivided into a receiving flue at one side of the exhaust pipe, and a delivering flue at the opposite side, and adapted to conduct a current of air from an inlet at one side of the forward end of the drum to an outlet at the forward end of the opposite side, and communicating with the vehicle body, so that the current passes in two opposite directions along the exhaust pipe, and is heated during its entire passage.

Another object is to provide a drum construction adapted to prevent gases which may percolate through the wall of the exhaust pipe from contaminating the air flowing through said flues.

I attain the above-mentioned and other related objects by the improved construction hereinafter described and claimed.

Of the accompanying drawings forming a part of this specification,—

Figure 1 shows in side elevation a portion of an exhaust pipe and an air-heating attachment embodying the invention associated therewith, and in section a portion of the floor of a motor vehicle body.

Figure 2 is a section on line 2—2 of Figure 1.

Figure 3 is a longitudinal section of the exhaust pipe, and a drum composed of sections assembled thereon, taken on line 3—3 of Figure 2.

Figures 4 to 7, inclusive, are fragmentary perspective views, showing portions of the body sections hereinafter described.

Figures 8 and 9 show in perspective the sections of one of the heads hereinafter described.

Figure 10 is an end view of the drum, and shows the exhaust pipe in section.

The same reference characters indicate the same parts in all of the figures.

In the drawings *a* designates a portion of the exhaust pipe of an internal combustion engine, having the usual muffler *b*. *c* designates a portion of the floor of the vehicle body.

My improved heating attachment comprises a drum composed of body sections and head sections formed to be assembled on the exhaust pipe, and clamping bolts connecting the sections and confining the same in assembled relation on the exhaust pipe, the preferred form of said sections being as hereinafter described.

The sections collectively form a longitudinal air-receiving flue 12, extending along one side of the drum from the forward to the rear end, and a longitudinal air-delivering flue 13, extending along the opposite side of the drum, from the rear to the forward end. An air inlet 14, preferably a forwardly extending tube, communicates with the receiving flue 12.

Said flue is connected at the rear end of the drum with the rear end of the delivering flue 13, preferably by ports or openings 15, formed in the partition portions hereinafter described. The forward end of the delivering flue 13 is provided with an air outlet 16, formed by a pipe extending to a register 17 in the floor *c*.

The arrangement is such that air admitted at the inlet 16, passes through the receiving flue 12, along one side of the exhaust pipe, and through the delivering flue along the opposite side of the exhaust pipe, the reversely flowing current absorbing heat from the entire portion of the exhaust pipe enclosed by the drum.

The preferred construction and connection of the drum sections are as next described.

The body of the drum is formed in part by a pair of longitudinally extending inner body sections, the rear ends of which are formed as shown by Figures 4 and 5. Each inner body section includes an arched sleeve-forming portion 18, and two partition-forming portions 19, projecting oppositely from the sleeve-forming portions.

The partition-forming portions are abutted together and collectively form a partition between the flues 12 and 13. The sleeve-forming portions collectively surround and conform closely to the exhaust pipe and said portions and the partition portions prevent gases which may percolate through the wall of the exhaust pipe from contaminating air passing through the flues, it being known that gases sometimes escape in small quantities through the wall of the exhaust pipe.

The ports or openings 15, connecting the

flues 12 and 13, are formed in the partition portions 19.

The outer wall of the drum is formed by two outer body sections including arched wall-forming portions 20, and longitudinal flanges 21, projecting from opposite edges of the portions 20, as shown by Figures 6 and 7. The flanges 21 are seated on the partition portions 19, and secured thereto by 10 clamping bolts 23, as shown by Figure 2.

The outer body sections are provided at their opposite ends with arcuate flanges 24, to which the heads forming the ends of the drum are secured by clamping bolts 25, as 15 shown by Figure 3.

Each head is composed of two sections 26, formed as shown, by Figures 8 and 9. The marginal portions of the head sections are secured by the clamping bolts 25, to the end 20 flanges 24. The head sections are provided with lateral flanges 27, which are seated on each other and connected by clamping bolts 28, as shown by Figure 10. Between the 25 flanges 27 are arched flanges 29, which collectively embrace portions of the exhaust pipe at opposite ends of the drum, as shown by Figures 3 and 10, and are secured to the exhaust pipe by set screws 30.

In assembling the sections the inner body 30 sections are applied to the exhaust pipe, the outer body sections are then applied to the partition portions 19, and secured thereto by the clamping bolts 23, and the heads are then applied to the ends of the outer body 35 sections and secured thereto by the clamping bolts 25. Finally the arched flanges 29 of the head sections are secured by the set screws 30, to the exhaust pipe.

The air inlet pipe 14 may be extended to a 40 point near the radiator of the engine, and its open forward end may be provided with a damper 32, which may be opened and closed by any suitable means controlled by the driver. When heat is not desired in the 45 vehicle body the damper may be closed.

Packing layers 33 of compressible material may be interposed between the partition-forming portions 19, to prevent gases from the exhaust pipe from reaching the air ports 50 or openings 15, and entering the flues, openings coinciding with the openings 15 being formed in the packing layers. Annular packing layers 34 may be interposed between the arched flanges 29 on the head and 55 the corresponding portions of the exhaust pipe.

I claim:

1. A motor vehicle heating attachment comprising a drum composed of body sections and head sections, formed to be assembled on a portion of an engine exhaust pipe extending lengthwise of the vehicle, and clamping bolts connecting said sections and confining the same in assembled relation on the exhaust pipe, the sections collect-

tively forming longitudinal air-receiving and delivering flues connected with each other at the rear end of the drum, one section having an air inlet at the forward end of the drum, communicating with the receiving flue, another section having an air outlet at the forward end of the drum, communicating with the delivering flue, the arrangement being such that air admitted at the inlet passes through the receiving flue 75 along one side of the exhaust pipe, and through the delivering flue along the opposite side of the exhaust pipe to the outlet, two of the body sections forming a sleeve 80 which closely embraces the exhaust pipe and prevents gases therein from entering the said flues.

2. A motor vehicle heating attachment comprising a drum composed of body sections and head sections, formed to be assembled on a portion of an engine exhaust pipe extending lengthwise of the vehicle, and clamping bolts connecting said sections and confining the same in assembled relation on the exhaust pipe, the sections collectively forming longitudinal air-receiving and delivering flues connected with each other at the rear end of the drum, one section having an air inlet at the forward end of the drum, communicating with the receiving flue, another section having an air outlet at the forward end of the drum, communicating with the delivering flue, the arrangement being such that air admitted at the inlet passes through the receiving flue along one side of the exhaust pipe, and through the delivering flue along the opposite side of the exhaust pipe to the outlet, the body sections including a pair of inner and a pair of outer sections, the inner sections having portions forming a sleeve embracing the exhaust pipe, and also having portions forming a partition between the receiving and exhaust flues, the outer sections forming the outer walls of the flues, while the sleeve and partition-forming portions of the inner sections form the inner walls of the flues.

3. A motor vehicle heating attachment comprising a drum composed of body sections and head sections, formed to be assembled on a portion of an engine exhaust pipe extending lengthwise of the vehicle, and clamping bolts connecting said sections and confining the same in assembled relation on the exhaust pipe, the sections collectively forming longitudinal air-receiving and delivering flues connected with each other at the rear end of the drum, one section having an air inlet at the forward end of the drum, communicating with the receiving flue, another section having an air outlet at the forward end of the drum, communicating with the delivering flue, the arrangement being such that air admitted at the inlet passes through the receiving flue 115 120 125 130 135 140 145 150 155 160 165 170 175 180

- along one side of the exhaust pipe, and through the delivering flue along the opposite side of the exhaust pipe to the outlet, the body sections including a pair of inner 5 and a pair of outer sections, the inner sections having portions forming a sleeve embracing the exhaust pipe, and also having portions forming a partition between the receiving and exhaust flues, the outer sections 10 forming the outer walls of the flues, while the sleeve and partition-forming portions of the inner sections form the inner walls of the flues, the ends of the drum being formed by heads, each composed of two sections 15 clamped to the ends of the outer body sections and to each other, and provided with arched flanges embracing and secured to the exhaust pipe.
4. A motor vehicle heating attachment 20 comprising a drum composed of body sections and head sections, formed to be assembled on a portion of an engine exhaust pipe extending lengthwise of the vehicle, and clamping bolts connecting said sections 25 and confining the same in assembled relation on the exhaust pipe, the sections collectively forming longitudinal air-receiving
- and delivering flues connected with each other at the rear end of the drum, one section having an air inlet at the forward end 30 of the drum, communicating with the receiving flue, another section having an air outlet at the forward end of the drum, communicating with the delivering flue, the arrangement being such that air admitted at 35 the inlet passes through the receiving flue along one side of the exhaust pipe, and through the delivering flue along the opposite side of the exhaust pipe to the outlet, the body sections including a pair of inner 40 and a pair of outer sections, the inner sections having portions forming a sleeve embracing the exhaust pipe, and also having portions forming a partition between the receiving and exhaust flues, the last-mentioned 45 portions being provided with air ports connecting the said flues, and packing layers interposed between the partition-forming portions and provided with openings coinciding with the said air ports.
- In testimony whereof I have affixed my signature.

LOUIS MACHADO.
